UNITED STATES PATENT OFFICE.

EMANUEL F. BUCH, OF MANHEIM TOWNSHIP, LANCASTER COUNTY, PENNSYLVANIA.

LINE-GUIDE.

No. 806,102.

Specification of Letters Patent.

Patented Dec. 5, 1905.

Application filed July 6, 1905. Serial No. 268,472.

To all whom it may concern:

Be it known that I, EMANUEL F. BUCH, a citizen of the United States, residing at Manheim township, in the county of Lancaster and State of Pennsylvania, have invented new and useful Improvements in Line-Guides, of which the following is a specification.

This invention relates to improvements in a line-guide of that class in which a metallic plate supports a specially-constructed rod and which plate is secured to the inner surface of the front end wall of a closed vehicle-body like that of a milk-wagon or a baker's delivery-wagon.

The object of the invention is to provide the bodies of such wagons with line-guides whereby the lines used by the drivers of such wagons may be conveniently adjusted and held in place, always ready to be grasped by the hands of said drivers.

The elements of the invention will severally and at large appear in the following description and they will be separately or combinedly set forth or pointed out in the appended claims.

The purposes of the invention are attained by the devices and means illustrated in the accompanying drawings, with similar reference characters designating like parts throughout the several views, in which—

Figure 1 is a perspective view of a portion of the inside of a front end wall of such vehicle-body, showing the elements of the invention secured thereto with portions of a pair of lines in place. Fig. 2 is a vertical sectional view taken on the line $\alpha\alpha$ in Fig. 1, showing the parts in place as they appear when viewed practically from the right. Fig. 3 is a direct elevation of the metallic plate as it appears when detached from Fig. 1. Fig. 3^A is a direct plan of said plate as it appears when viewed from above in Fig. 3. Fig. 4 is a direct elevation of the specially-constructed rod as it appears when detached from said plate. Fig. 4^A is a direct plan of Fig. 4 as it appears when viewed from above. Fig. 5 is a sectional elevation taken on the line $\gamma\gamma$ in Fig. 4 as it appears when viewed from the left.

In the drawings, A designates the lower portion of the front end wall, which consists of the outside casing α and the inside casing α' , which are rigidly secured to the sides of a central post A' in any approved manner and to the usual end posts, (not here shown,) leav-

ing the usual space or opening α^2 between the casings for the purpose of receiving the window-sashes when they are lowered for the purpose of opening the upper portion of said front end wall, which opening is adapted to be closed by a lid A², hinged at its side edge 55 to the inner casing by hinges A³, secured in place by screws α^3 , which lid is adapted to support the lower side rails of the sashes when they are lowered for the purpose of closing the upper portion of said front end wall and 60 having their lower edges provided with cut-out recesses α^4 , adapted to have freely seated therein the straps of the lines A⁴, said central post being provided in the sides thereof with guide-grooves α^5 , into which are seated 70 the side posts of the sashes 1, movable up and down therein, and the post having at the required point its body cut away, forming an opening α^6 for the passage of the lines, as will be hereinafter explained.

Against the inner surface of the casing α' , adjacent to the upper edge thereof, is rigidly secured in any approved manner a base-plate B, having at its upper edge a side projecting ledge b, said ledge being somewhat centrally 80 provided with upwardly-projecting ears b', forming an opening b² to register with the opening α^6 of said central post A'. For the purpose of strengthening the central post, which has been weakened by the opening α^6 85 cut through its body, there is placed over said opening a vertically-disposed rectangular bar B', somewhat clevis shape in form, provided with end extended ears b⁰, through which headed bolts with nuts B⁰ on their threaded 90 ends serve to secure said bar in place, the lower ear B⁰ being placed against the adjacent surface of the base-plate B, with screws B⁴ passed through both of said ears adjacent to the ends thereof and tapped into the body of 95 said post. To the body of said base-plate B is adjustably secured the specially-constructed rod B², which rod in this instance is made in two parts b³ and b⁴, projecting upwardly from plates b⁵, with scroll ends b⁶ at the outer extremities thereof and at the inner extremities with inclined bars 2, conforming to the inner 100 sides of the ears b' of the plate B, and in the bodies of the plates b⁵ are formed horizontally-disposed oblong slots b⁷, through which bolts and nuts B⁸ serve to adjustably secure said parts b³ and b⁴ in place. At the required points said parts are formed with notches or open-

105

ings b^8 for the purpose of giving passage to the line-straps A^4 , before mentioned, extending over said openings. Said parts are formed with curving arms b^9 , having downwardly-projecting end hooks b^{10} for the purpose of holding said line-straps in place. Said parts are also provided with openings b^{11} for the purpose of reducing weight.

It will here be remarked that by reason of said opening b^2 between the ears b^1 and the opening a^6 of the central post A' the line-straps may be changed at pleasure, so that said straps may occupy places on the right and left of the central post when so desired.

15 The invention having thus been ascertained and described and the manner in which its functions are performed fully shown and set forth, what is considered new, and desired to be secured by Letters Patent, is—

20 In a line-guard the combination with the lower portion A of the front end wall having the outside casing a and the inside casing a' with the open space a^2 therebetween, and the hinged lid A^2 to cover and uncover said open

25 space; the central post A' with the cut-out opening a^6 through its body and the sash-guide grooves a^5 in side edges thereof, with the side posts of the sashes 1 in engagement with said grooves, said sashes having through

their under edges in the lower side rails thereof of the line-guide notches a^4 ; the base-plate B , rigidly secured to the surface of the inside casing a' adjacent to the upper edge thereof, said plate having the upper-edge side projecting ledge b with the upwardly-projecting ears b^2 forming therebetween the opening b^2 to register with the opening a^6 of the post A' ; the clevis-shaped bar B' placed over said opening a^6 and the end ears b^6 rigidly secured to the adjacent surface of said post with the lower ear b^9 in contact with the adjacent surface of said plate B ; the line-guide rod B^2 comprising the parts b^3 and b^4 projected upward from the plates b^5 and by reason of the oblong slots b^7 adjustably secured to the body of the base-plate B , said rod portions having the extreme end scrolls b^6 , the inner-end inclined bars 2, the line-guide notches b^8 , the curving guide-arms b^9 with the end retaining-hooks b^{10} , and the weight-reducing openings b^{11} ; all substantially as described and for the purpose hereinbefore set forth.

In testimony whereof I affix my signature in presence of two subscribing witnesses.

EMANUEL F. BUCH.
